Inventor.

James A. Lewis

UNITED STATES PATENT OFFICE.

JAMES A. LEWIS, OF BINGHAMTON, NEW YORK.

STREET-RAILWAY-TRACK CLEANER.

SPECIFICATION forming part of Letters Patent No. 399,421, dated March 12, 1889.

Application filed February 15, 1888. Serial No. 264,154. (No model.)

To all whom it may concern:

Be it known that I, JAMES A. LEWIS, a citizen of the United States, residing at Binghamton, in the county of Broome and State of New York, have invented certain new and useful Improvements in Street-Railway-Track Cleaners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Similar letters refer to similar parts throughout the several views.

The nature of this invention is that of an improved track-cleaner for street-railways; and the improvements consist, first, in the means for raising, lowering, and carrying it at any required height; second, in the method of its attachment to the car; third, in a means of widening and narrowing the sweep of the cleaner, as required.

In the accompanying drawings, Figure 1 is the plan of the cleaner as seen from the under side. Fig. 2 shows the dog-wheel with a toothed ratchet upon its upper face fastened upon the shaft B, upon which the chain winds, which serves to raise and hold up the scrapers. Fig. 3 is a detailed representation of the means for extending and contracting the sweep of the scrapers. Fig. 4 shows the lower end of the shaft upon which the chain winds for raising and lowering the scrapers, the dog, dog-wheel, and box, with the chain wound on the shaft. Fig. 5 is an elevation in perspective, showing the means of attaching to the floor of the car, of raising and lowering the scraper, and the shaft and crank for effecting this purpose.

S S, Fig. 1, are scrapers, made, preferably, of shear-steel, clamped at the upper inside corner between the bars E and F. The scrapers may be made with a detachable shoe at the bottom, which can be replaced when worn; but as this is a common device it is not shown in the drawings. Each of the scrapers has attached to it at the top a chain, C, running over the pulley P, for raising and lowering the scraper. The chains extend to the mid-

dle of the car, coming together as shown in Fig. 1, and are attached to the chain C', which winds around the shaft B. (Shown in Figs. 4 and 5.) It is obvious that by this arrangement the scrapers are raised or lowered simultaneously and equally.

The bars or braces E and F are pivoted to the hangers G upon the under side of the car and furnish a hanging support for the scrapers both strong and flexible. The sweep of the scrapers is regulated by the inner bars, F F, which are made in two sections each and joined together, as shown at H, Fig. 1, and two sections are shown in larger size in Fig. 65 3. The toothed faces fitting snugly into each other are held firmly together by the bolt extending through the slot f in them, so that they may be extended until but a single tooth on each laps on the other, or shortened until 70 the teeth lap nearly past each other. By means of this lengthening and contracting arrangement light snow may be removed the short distance necessary to clear the track, or heavier snow may be swept away as far as 75 required. It will be observed that the slot f extends nearly the entire length of the tooth portion of the bar F. It will thus be seen that the necessity of entirely removing the clamping-bolt when it is desired to adjust the 80 length of the bar F will be obviated, and such adjustment is therefore greatly facilitated.

At the front end of the car, either inside or outside of the upright end of the car, as desired, is the upright shaft B, having a crank, 85 B', at the top for winding up the shaft. At the level of the floor on this shaft is the dog-wheel A, (shown in detail in Fig. 2,) covered by the box L, through the top of which the shaft B passes. Inside the box is the dog D, 90 Fig. 4, pivoted at d, with the tooth of the dog resting in the ratchet on the dog-wheel. Jointed to the other end of the dog is a pin or bolt, S, extending up through the top of the box, having at the top a broad head, and 95 upon the bolt, between the head of the bolt and the top of the box, is a coiled-wire spring, S', acting upon the bolt-head and holding it up, thus keeping the tooth down in the ratchet. The operation of this raising and lowering device will be readily understood by observing 100 that when the crank B' is turned the chain C'

winds upon the lower end of the shaft and raises the scrapers. The dog held down upon the ratchet of the dog-wheel by means of the coiled-wire spring S', lifting at the other end, 5 serves to rigidly hold the scraping mechanism in any desired position. To lower the scraper the driver presses his foot upon the bolt-head, bearing down upon the bolt and spring, thus lifting the tooth of the dog and releasing the 10 dog-wheel.

By means of the bracing-bars E and F a steady and strong support to the scrapers is secured, and any width of sweep may be had by taking up or letting out at the toothed 15 joint H.

Having thus described my invention and its construction, what I claim as new, and desire to secure by Letters Patent, is—

1. In a track-cleaner for street-railway cars, 20 the track-scrapers S, suspended by chains running over pulleys and which are connected together near the shaft upon which they wind up, in combination with brace-bars E and F, for holding the scrapers in position, the inner 25 brace-bar, F, having a toothed and slotted splice by which the sweep of the cleaner may be extended or contracted, substantially as shown and described.

2. In a track-cleaner for street-railways, the 30 combination, with track-scrapers, of bars or braces, between the forward ends of which the track-scrapers are clamped, and hangers depending from the bottom of the car and having the rear ends of the bars or braces 35 pivoted thereto, substantially as shown and described.

3. In a track-cleaner for street-railways, the combination, with track-scrapers, bars, or braces, between the forward ends of which the track-scrapers are clamped, and hangers 40 depending from the bottom of the car and having the rear ends of the bars or braces pivoted thereto, of a suspending-chain, as C, for each of the scrapers, running over a pulley secured to the car-bottom and extending 45 diagonally toward each other, a chain, such as C', connecting the rear extremities of the chains C, and a vertical shaft upon which chain C' winds, all substantially as and for the purposes herein set forth. 50

4. In a track-cleaner for street-railways, the combination, with track-scrapers, of bars or braces situated in pairs, between the forward ends of which the track-scrapers are clamped, and the inner bar of each of which pairs has 55 a toothed and slotted splice, substantially as and for the purposes herein set forth.

5. In a track-cleaner for street-railways, track-scrapers and means for suspending the same, in combination with bars or braces for 60 holding the scrapers in position, situated in pairs, the inner bar of each of which is formed in two parts and with intermeshing teeth at the point of junction, and also with an elongated slot, and a pin or bolt extending through 65 the said slot and adapted to clamp the two portions of the inner bar together.

JAMES A. LEWIS.

In presence of—
NERI PINE,
H. C. WOOD.
